US0D1032933S

(12) **United States Design Patent** (10) **Patent No.:** **US D1,032,933 S**
(45) **Date of Patent:** **** Jun. 25, 2024**

(54) **AEROSOL GENERATING DEVICE**

(71) Applicant: **Philip Morris Products S.A.**,
Neuchâtel (CH)

(72) Inventor: **Kwang Beng Tan**, Sai Wan Ho (HK)

(73) Assignee: **Philip Morris Products S.A.**,
Neuchâtel (CH)

(**) Term: **15 Years**

(21) Appl. No.: **29/922,048**

(22) Filed: **Dec. 20, 2023**

(57) **CLAIM**

The ornamental design for an aerosol generating device, as
shown and described.

DESCRIPTION

FIG. 1 is a front, top, and left side perspective view of an
aerosol generating device showing the new design.

FIG. 2 is a front elevational view thereof.

FIG. 3 is a rear elevational view thereof.

FIG. 4 is a top plan view thereof.

FIG. 5 is a bottom plan view thereof.

FIG. 6 is a right side elevational view thereof.

FIG. 7 is a left side elevational view thereof; and,

(Continued)

FIG. 8 is another front, top, and left side perspective view thereof.

The grey scale shadings show contours and neither ornamentation, nor coloration, nor surface finishing.

1 Claim, 8 Drawing Sheets
